DESIGN FOR A DRESS

Madeleine Croizat, New York, N. Y.

Application September 22, 1939, Serial No. 87,338

Term of patent 3½ years

To all whom it may concern:

Be it known that I, Madeleine Croizat, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

Fig. 2 is the rear view thereof.

The characteristic feature of my design resides in the combination on the princess dress disclosed of the specific sequin trim arranged on the hood collar as shown.

I claim:

The ornamental design for a dress, substantially as shown and described.

MADELEINE CROIZAT.
